FENCE WIRE SPACER

Jack L. Jackson, Phoenix, Ariz.
(Rte. 1, Box 101, Columbus, Mont. 59101)

Filed Sept. 13, 1973, Ser. No. 397,089

Term of patent 14 years

Int. Cl. D25—01

U.S. Cl. D28—1 R

fig. 4

fig. 5

fig. 3

fig. 6

FIG. 1 is a front perspective view, of a fence wire spacer showing my new design, the broken line disclosure being for illustrative purposes only and forming no part of the claimed design;

FIG. 2 is an enlarged fragmentary side elevational view thereof;

FIG. 3 is a side elevational view thereof showing the spacer in open condition;

FIG. 4 is a top plan view thereof;

FIG. 5 is an enlarged fragmentary elevational view as seen in the direction of arrows 5—5 of FIG. 3; and

FIG. 6 is an enlarged perspective view thereof.

I claim:

The ornamental design for a fence wire spacer, as shown and described.
